UNITED STATES PATENT OFFICE.

EDGAR J. THOMAS, JR., OF PHILADELPHIA, PENNSYLVANIA.

DESIGN FOR A GAME-BOARD.

SPECIFICATION forming part of Design No. 25,965, dated August 18, 1896.

Application filed July 2, 1896. Serial No. 597,904. Term of patent 3½ years.

To all whom it may concern:

Be it known that I, EDGAR J. THOMAS, Jr., a citizen of the United States, residing in the city and county of Philadelphia, State of Pennsylvania, have invented and produced a new and original Design for a Game-Board, of which the following is a specification, reference being had to the accompanying drawings, forming part thereof.

10 The leading feature of my design for a game-board is a field having thereon a diamond-shaped channel and other channels extending from the angles of said diamond-shaped channel and a circumferential channel with which the other channels communicate.

Figure 1 represents a plan view of a game-board embodying my design. Fig. 2 represents a diametrical sections thereof on line 20 *xx*, Fig. 1.

In the drawings, A designates a field on which are the diamond-shaped channel B, the segmental channels C D, the branch channels E, and the circumferential channel F. The branch channels E extend from opposite angles of the channel B, and the segmental channels C D extend from the other angles thereof. The channels C D and E meet the circumferential channel F. In a portion of the field are pockets G. 25

What I claim is—

30 The design for a game-board substantially as described and shown.

EDGAR J. THOMAS, JR.
